GAS BURNER

Application filed December 22, 1930. Serial No. 503,951.

This invention relates to improvements in gas burners and more particularly to gas burners of the types adapted for domestic cooking and heating purposes.

5 Until recently practically all of the gas burners employed in connection with domestic and other heating appliances have been designed to be supplied with either manufactured or natural gas, or mixtures thereof. 10 However, since the advent of gas sold commercially in portable containers, in highly compressed, sometimes in liquid form, there has been created a demand for gas burners of different construction than the types 15 of burners adapted only for connection with gas supply mains. For example, the older types of burners do not operate efficiently when supplied with the heavier hydrocarbon gaseous fuels constituting or entering into 20 the composition of the high test gases such as are now dispensed commercially in containers. The desirability of burners of a different construction, for operation with high test gases will be appreciated when it is considered that manufactured gas from the usual 25 sources possesses a heat value rarely in excess of six hundred B. t. u. per cubic foot, while the so called bottle gases or high test gases possess a heat value approximating 30 twenty-five hundred B. t. u. per cubic foot.

By way of a general, although not a universal distinction, it may be noted that most of the high test gases referred to are heavier than air, whereas illuminating gases heretofore usually supplied for domestic uses are lighter than air.

An object of this invention therefore is to construct a gas burner which provides mixing facilities for a heavier-than-air gaseous fuel; the burner construction being such that it is enabled to operate satisfactorily and economically not only with heavier or high test fuels, but also on natural gas and artificial gas of the 45 usual composition.

An additional object of the invention is so to construct a gas burner that it may be employed in connection with gas stoves for cooking and other purposes as now manufactured, 50 without necessitating any extensive structural

changes in the assemblies heretofore manufactured, apart from the burners.

A further object of the invention is the provision of a gas burner including a reservoir or mixing space within the burner which exceeds substantially in size the space provided below the burner ports in prevailing types of gas burners, and such that the gas and air will be more completely mixed before issuing through the burner ports, and also of such a size and proportion relative to the total area of the burner ports, that the gaseous fuel is issued, for burning, only in completely and homogeneously aerated form. 55

Yet a further object of the invention is attained in the design and construction of a gas burner fulfilling the requirements, and having the characteristics above noted, and yet which can be manufactured economically, 60 with precision, and with uniformity. 65

Additional objects and advantages of the present invention will appear from the following detailed description of a single preferred embodiment thereof considered in connection with the accompanying drawing, in 70 which:

Fig. 1 is a plan view of one form of burner of my invention, Fig. 2 is an elevation of the burner, partly in section, along the line 2—2 of Fig. 1, and Fig. 3 is a section of the burner 75 along line 3—3 of Fig. 1.

Referring now by numerals of reference to the drawing, the burner is adapted for connection at an opening 3, to a gas cock which may be of conventional construction and 80 from which the flow of gas from a suitable supply conduit, (not shown), is directed into an enlarged open end mixing throat 4 of a fuel supply passage or mixing tube indicated generally at 5. The internal conformity 85 of the tube 5 is such as to constitute a Venturi passage, the relatively constricted portion of this passage being indicated at 6. Disposed as a closure for the end 4, is an air shutter 7, which may be disposed for a limited 90 angular movement over the inlet opening to the throat 4, so as to control the volume of air admitted thereto. The air shutter may be of any suitable form. 95

An advantage of the burner construction, 100

to be hereinafter described in more detail, is found in that it does not require a mixing passage of any great length, since provision is made in the burner head for thoroughly mixing the primary air with the gaseous fuel. As appears, therefore, the passage 5 may be relatively short without adversely affecting the quality of the mixture obtained. This is of advantage, particularly in connection with burners disposed in the forwardmost row on the cooking top of gas stoves or ranges. On account of the small length of mixing passage heretofore provided into a forward burner from the gas supply manifold, more difficulty has been experienced in the case of high test gases, with the front row of burners than with the rear, since the greater length of supply passage between each of the rear burners and the gas supply, has, of itself, afforded a certain greater gas mixing space.

Proceeding now to a description of the body of the burner head, there is provided, as constituting the lowermost portion of the burner head structure, a mixing well or reservoir indicated generally at 8, and which by preference is of circular transverse section and hence of cylindrical contour, and has connection, at one side of its lowermost portion, with the passage 5. The reservoir 8 is, by preference of annular form, due to the provision of a central through-aperture 9, conveniently disposed as shown to insure an ample supply of secondary air. The reservoir 8, as appears particularly from Fig. 2, is so formed that the burner is of substantially greater depth and volume than is the practice, or is necessary, in burners designed to consume only gaseous fuels of lighter-than-air types. In the construction shown by the drawing, the capacity of the burner head, including the mixing well, is substantially in excess of the capacity of the passage 5. According to the preferred arrangement the upper portion of the mixing reservoir is characterized by a plurality of angularly spaced, radial arms 10, in the present example these arms being disposed ninety degrees apart and each characterized by a substantial internal volume so that each arm forms a lateral extension of the upper portion of the mixing chamber, and terminates upwardly in a plurality of burner ports 11. My preference is to form each of the arms 10 of greater width than has been the practice with burners of older types and instead of employing only a single row of ports on each arm, to provide an aggregate burner port area consistent with the volume of the reservoir 8, by disposing the ports 11 in plural, preferably parallel rows on each of the arms. In addition, and as best appears in Fig. 1, the rows of burner ports may be continued about the center of the burner head to form a ring of ports 12.

As may be desired, and as presently pre-

ferred, there is also provided adjacent the periphery of passage 9, an inner ring of burner ports 13, four of which are shown, and which are directed at an angle to the vertical, as best appears in Fig. 2. It is also my preference to dispose the ports 11 and 12 at a substantial angle to the vertical so that the flames issuing from these ports provide for a better spread or distribution of heat just above the burner head.

As a convenient provision for partial or complete support for the burner assembly, the burner head is shown as provided with a T-shaped extension 14, centrally reinforced by a rib extending longitudinally of the upper surface of the extension, and shown at 15, the extension being formed integrally with the burner head, as shown, or as a separate member secured thereto. This extension may in turn rest upon a suitable, preferably horizontal portion of the stove frame structure, as is well known in the art. Such a frame member may be apertured, and to provide means for preventing lateral movement of the burner, there is provided an extension 16 which may project downwardly through such an aperture and thus position the burner laterally of the stove or other associated structure.

It will appear from the foregoing description that the described burner, when employed with heavier-than-air gaseous fuels, results in a fuel-air mixture collecting on the imperforate bottom surface of the mixing reservoir 8. Since a fuel, or a fuel-air mixture of this type moves relatively slowly and does not tend, of itself, to rise through the burner ports, the mixture must be displaced upwardly by additional incoming fuel, resulting in a sufficient increase in pressure to cause a discharge of combustible mixture through the ports, such as 11. The present burner is thus distinguished by the provision of an internal chamber or space of several times the size usual in a burner head of given area, and further characterized by an imperforate wall portion, being in the present case the bottom of the burner, against which the incoming fuel or air-fuel mixture tends to collect, and from which it is positively displaced upwardly. The volume of the reservoir 8 is such that, considering the low rate of movement of the heavier gases, a thorough circulation of gas and mixture thereof with air, occurs in the mixing reservoir prior to issue of the gas for burning. It will thus appear that the burner described provides an efficient means for burning fuels of the type for which it is particularly adapted, and fulfills the several objects set forth above.

The invention has been described by making specific reference to a presently preferred executional embodiment of the invention. The description is, for this reason, to be understood solely in a descriptive, and not

in a limiting sense, since, as will appear to those skilled in the art, various changes may be made in the parts, their combinations and assembly, or certain of the parts may be omitted, and equivalents substituted or parts added, without departing from the spirit and full intended scope of the invention, as defined by the appended claims.

I claim as my invention:

- 10 1. In a burner for gaseous fuels, a burner head having a relatively deep centrally disposed well portion adapted as a mixing reservoir, a central opening through said reservoir for secondary air, radially extending chambered arm portions disposed on the upper part of said reservoir, and each opening upwardly into a plurality of rows of burner ports arranged in parallel adjacence, an inner circle of burner ports disposed closely about the upper end of the opening through said reservoir, an outer circle of burner ports disposed between said inner circle and the parallel rows of ports in said radial portions, and a fuel supply conduit opening into a side wall of said reservoir, below and between a pair of said arm portions.
- 20 2. In a gas burner assembly, a burner head of substantial depth and hollow annular form, the side walls thereof being relatively divergent from the top of the head to points defined by a transverse median plane, said walls being substantially parallel below such plane, a fuel supply pipe extending laterally of the head and adapted for communication with a source of fuel, said pipe opening into the head through the outer, substantially parallel wall, chambered arm portions extending radially of the head, disposed above the median plane, the under surfaces of said arms sloping upwardly and outwardly, a supporting bracket extending from the side of the burner head opposite said pipe and constituting a substantially T-shaped ex-
- 30 35 40 45 50 tension therefrom, said bracket including a reinforcing rib extending longitudinally of the arm and disposed centrally thereof, and a projection disposed beneath the arm and independently of the outer end thereof.

SWINEY MORGAN.
